UNITED STATES PATENT OFFICE.

FRANCIS X. GANTER, OF BALTIMORE, MARYLAND.

REVOLVING SHOW-CASE.

SPECIFICATION forming part of Letters Patent No. 398,604, dated February 26, 1889.

Application filed April 14, 1888. Serial No. 270,663. (No model.)

To all whom it may concern:

Be it known that I, FRANCIS X. GANTER, a citizen of the United States, residing at Baltimore, in the State of Maryland, have invented 5 certain new and useful improvements in Revolving Show-Cases, of which the following is a specification.

My invention relates to an improvement in show-cases, which is illustrated in the accompanying drawings, in which—

Figure 1 is a front view of the case. Fig. 2 is a rear view showing the display-stand with one door or back and partly turned. Fig. 3 is a cross-section on the line 3 3, showing the 15 display-stand in the same position it has in Fig. 2. Fig. 4 is a rear view of the show-case, showing two doors. Fig. 5 is a side view of the case, showing one of the two doors partly open and one of the two sections of the 20 display-stand attached to each door. Fig. 6 is a horizontal cross-section on the line 6 6, showing one action of the display-stand open and one closed.

The glass front A of the show-case is semi- 25 cylindrical. The base b and the top c are half-circular at the front d, and diametrically straight across at the back e. Both the base and top have at the straight back a pivot, f, at the center, and the case is open at the back.

30 The display-stand G consists of shelves receding from the bottom upward and back, like steps, and is half-circular in front, and has a flat door or back, h, which is suspended by

the said top and bottom pivot f on the show-case. The display-stand and door or back 35 may be in one piece or structure, as shown in Figs. 1, 2, and 3, or may be in two sections, G G', each separately movable and both suspended from the same pivots, as shown in Figs. 4, 5, and 6. Each door or back has a 40 spring-bolt, i, or other suitable fastening, and may have drawers k, which open outward through the back, and when in occupy the space back of and below the shelves G.

By swinging the display-stand on their pivot 45 f the shelves are turned outward away from the inclosing-case A, and access is thereby had to them.

Having described my invention, I claim—
The combination, in a show-case, of an in- 50 closing-easing having a semi-cylindrical transparent front, and a display-stand provided with a series of semi-cylindrical step-like shelves in front, and a flat door or back, and recesses having drawers at the rear, the display-stand being pivoted within the casing, as described, whereby it may be turned to insert the articles to be displayed, substantially as shown and described.

In testimony whereof I affix my signature in 60 the presence of two witnesses.

FRANCIS X. GANTER.

Witnesses:

JOHN E. MORRIS,
JNO. T. MADDOX.
